UNITED STATES PATENT OFFICE.

ALVAN MACAULEY, OF ST. LOUIS, MISSOURI, ASSIGNOR, BY MESNE ASSIGNMENTS, TO BURROUGHS ADDING MACHINE COMPANY, OF DETROIT, MICHIGAN, A CORPORATION OF MICHIGAN.

ADDING-MACHINE.

1,148,110.

Specification of Letters Patent. Patented July 27, 1915.

Application filed July 1, 1904. Serial No. 214,921.

To all whom it may concern:

Be it known that I, ALVAN MACAULEY, a citizen of the United States, residing at the city of St. Louis, in the State of Missouri, 5 have invented certain new and useful Improvements in Adding-Machines, of which the following is a specification.

My invention relates to what are commonly known as adding machines, by which 10 individual items are printed, listed, and added, and the object of my invention is to provide a machine of this character with means or mechanism under the control of the operator for throwing the adding mechanism proper out of action whenever it is 15 desired to print a number or series of numbers without adding or accumulating them, with the result that the machine will perform its usual functions of printing as before, but the adding function of such machine will be eliminated so long as said means remains in operative position.

My invention also contemplates the provision of means actuated in connection with 20 said newly provided mechanism and coöperating with a laterally movable paper carriage for advancing or shifting such carriage to different columnar positions and also means for controlling the vertical feed 25 of the paper on the platen.

My invention is more particularly designed as an improvement upon what is commonly designated the "Burroughs" adding machine, as illustrated and described, 30 for instance, in Letters Patent of the United States Nos. 504,963 and 505,078, issued to William S. Burroughs on September 12, 1893, but it will be understood that the same is not limited in its application to the Burroughs machine, but may be embodied and 35 incorporated in machines of similar character and intended for similar purposes.

In the drawings, Figure 1 is a sectional elevation of the left hand side of a Burroughs adding machine showing my invention embodied therein and used in connection with the usual and well known parts of such machine; Fig. 2 a rear elevation of my improved machine; Fig. 3 an elevation of 40 the attachment or parts comprising my invention together with certain main operating parts of a Burroughs machine with which parts my attachment directly coöperates; Fig. 4 a detail view of the outer end 45 of my main operating lever showing the

wipe plate thereof; Fig. 5 a detail view of the usual wipe plate 821 of a Burroughs machine with a stud or pin secured thereto to work in connection with my attachments; Figs. 6 and 7 detail views showing different 60 relative positions of my attachment and some of the main operating parts of the machine; and Fig. 8 a perspective of the parts illustrated in Figs. 6 and 7.

Inasmuch as a Burroughs adding machine 65 is not only disclosed in said Burroughs patents, but is also well known as to construction and operation, a detailed description of the various parts will not be necessary, and consequently it will suffice to refer only to 70 the general operation of such machine and describe only those parts which are directly concerned with my invention.

As usual in a Burroughs machine, the machine herein illustrated is provided with 75 a keyboard having a plurality of rows of keys 221, extending from front to rear of the machine, the nine keys in each row representing the nine digits and having their key buttons numbered from 1 to 9 from 80 front to rear of the machine and the respective rows representing different denominations increasing from right to left. The keyboard is also provided with the well known "total" key 265, having the usual 85 connections for controlling the operation of the printing mechanism to print a total, whereby a total may be taken whenever desired by the operator.

The levers B, which correspond in number with the rows of keys, are hung upon the main rock shaft 600, Fig. 1, and carry at their rearward ends the usual type plates 618 and at their forward ends are operatively connected with the series of gear toothed racks 610. Each of these racks 610 coöperates and meshes with its adding wheel pinion 916 having an adding or dial wheel 912. The series of adding wheel pinions 916 are mounted in a frame C, which is arranged to rock on a transverse rod or shaft 900, with the result that during the movements of the main operating lever 367 such pinion frame is caused to be swung out of mesh with the racks.

The means for swinging the pinion frame comprises the arm 914 and the three-armed lever 913, to which the former is pivoted at its rearward end. This arm 914 is pivotally suspended at the lower end of a long sub- 100 105 110

stantially vertical link 911, which is operatively connected at its upper end with the bell crank 227 of the total key. The front end of the arm 914 has two diverging arms 5 or branches 914^a and 914^b, adapted and arranged to coöperate with the pinion frame in the well known way, with the result that the pinions are removed from engagement with their racks and reengaged therewith 10 at the proper times in order that upon the upward movement of the released or operated racks the pinions will be turned distances corresponding to the previous downward movements of the respective racks, 15 and the values of the operated keys thereby transferred to the adding wheels, it being borne in mind that upon the downward movement of these particular racks and upon the forward stroke of the operating 20 handle the pinions had been removed from engagement with the racks.

In operating a Burroughs machine, the item or amount is first set up on the keyboard and the operating handle is given a 25 complete stroke, that is a forward and backward movement, with the result that the main levers B corresponding to the particular rows of keys operated are moved distances corresponding to the value of the particular keys depressed, so as to bring the proper type plates adjacent the printing line of the platen and the amount or number is thereby printed. However, prior to the movement of these levers B the adding pinions are removed from mesh or engagement 30 with their racks so that when such racks or the particular ones operated move downwardly, they will not turn or rotate such pinions. At the completion of the forward 35 stroke of the operating handle the amount is printed and thereupon, on the return or backward stroke of the operating handle, and before the racks 610 are restored to normal position, the pinions are brought back 40 into engagement with such racks and are turned or rotated by such racks distances corresponding to the downward movement of the latter, with the result that the amount set up on the keyboard is accumulated on 45 the adding wheels.

The means for operating the arm 914 to swing the pinion frame and pinion out of operative engagement with the racks comprises the three-armed lever 813, mounted 55 on rock shaft 800, and the wipe block or plate 821, which is pivoted on the outer end of the arm 813^a of the lever 813. A spring 883 on the lever 813 tends to hold the wipe plate in alinement with its arm 813^a. The 60 wipe plate coöperates with the studs 961 and 961^a arranged at opposite sides or ends of the lever 913, with the result that when the operating handle is drawn forwardly and the shaft 800 thereby rocked, the wipe 65 plate 821 will contact the stud 961^a and

move the latter upwardly, thereby rocking the plate or lever 913 and forcing the arm 914 forwardly, whereupon the pinion frame and pinions will be swung forwardly out of engagement with their racks. In the rocking 70 of lever 813, the wipe plate 821 is carried rearwardly, and, upon the return stroke of the operating handle, normally coöperates with the stud 961 to move such stud and its end of lever 913 upwardly, with 75 the result that the arm 914 is drawn rearwardly and restored to normal position and the pinion frame and pinions are also restored.

As is well known, when the total key 265 is depressed and kept in that condition during both the forward and rearward movements of the operating handle 367, a "grand total" will be printed and the machine will be "cleared," but in case such total key is 80 kept depressed only during the forward movement of the operating handle and restored to its normal position just before or during the rearward movement of such handle, a "sub-total" will be printed, but 85 the machine will not be "cleared." When the total key is depressed, the downward movement thereof is communicated through the link 911 to the arm 914, with the result that the pinions are permitted to remain in mesh with their racks during the downward movement of the latter, whereupon the racks will descend distances corresponding to the values of the adding wheels associated with such pinions and the type plates will be 90 100 swung upward corresponding distances and the "total" will be printed. In the described descent of the racks the pinions will all be restored to zero. If now the "total" key is kept depressed upon the rearward or 105 return movement of the operating handle the pinions will be removed from mesh with their racks, with the result that the racks will first drop and then be restored to their normal elevated position, at which time the 110 machine is said to be "cleared." However, in case the total key is released and restored to normal position at the completion of the forward movement of the operating handle, the pinions will be left in mesh with the 115 racks and, upon the return movement of the operating handle, such racks will be raised to normal position and will restore to the pinions respectively the values taken off by the racks and theretofore indicated by the 120 pinions. This operation is known as taking a "sub-total."

The paper carriage arranged at the rear of the adding machine frame is laterally movable and adjustable to different columnar positions and adapted to receive the impressions from the printing mechanism of the adding machine. This paper carriage is of the same general construction and mode of operation as that illustrated and de- 125 130

scribed in Pike Patent No. 595,964, issued December 21, 1897, to the American Arithmometer Company. The paper carriage mechanism, however, differs in construction 5 and operation in several respects, as will be hereinafter made apparent.

In its usual operation and according to the normal conditions herein illustrated, the Burroughs machine has provision for feeding the paper vertically on the platen at 10 every full operation or complete stroke of the operating handle. To this end, one of the main rock shafts 100 of the machine is operatively connected to a vertical feed arm 15 1513 hung upon such shaft and carrying at its upper end an anti-friction roller 538. This feed arm is rocked rearwardly (to the left in Fig. 1) when the main operating handle is actuated, with the result that the 20 said anti-friction roller rocks an arm 30 upwardly and causes a second arm 31, which is mounted on the same shaft 32 as the arm 30, to actuate a bail or universal rod e^2 , with the result that the platen will be advanced 25 a certain predetermined distance upon the return movement of such bail. In the present instance, the paper feed mechanism is constructed and operated in the following manner, although it will be understood that 30 my invention is not limited to any particular construction.

Referring to Fig. 1, the platen 619 is provided at one end with a ratchet wheel 519, with which engages a spring-pressed 35 pawl 521 pivoted upon a plate 526 which is itself hung or pivoted upon the spindle of the platen. This pivoted plate 526 is operatively connected through the medium of a link d with a bell crank e . This bell crank 40 is secured to a transverse rod e' , to which the universal rod or bail e^2 is also secured. It will be readily understood that whenever 45 this universal rod or bail is rocked rearwardly, that is toward the left in Fig. 1, the bell crank e will be rocked and the plate 526 and pawl 521 swung in a clockwise direction (Fig. 1), whereupon such pawl will 50 slip by a predetermined number of ratchet teeth and upon the return movement of said 55 parts such pawl, being in engagement with the ratchet wheel, will turn or advance the platen a certain distance as predetermined by the particular point of attachment of the upper end of the link d with the swinging plate 526. The platen is thus advanced one line space upon the restoration of said 60 moved parts and only after the adding machine has printed the item or amount upon the paper on the platen.

65 The machine herein illustrated and hereinafter described normally operates as an ordinary Burroughs machine, but by the provision of my new mechanism or attachment the adding function or mechanism of such machine is eliminated or thrown out of

action whenever desired by the operator, and, at the same time, my attachment is designed to throw the vertical paper feed out of action as well as to control the transverse feed or shifting of the paper carriage, with 70 the result that when desired by the operator a number may be printed upon the platen without accumulating or adding and without vertical paper feeding and the carriage may be shifted or advanced to the next columnar position to enable a second number 75 or value to be printed by the machine on the same horizontal line, and so on according to the capacity of the paper carriage as to longitudinal shifting or adjustment. 80 By these means a series of items may be printed on the same horizontal line, some of which items, which may be termed numbers, may be printed without accumulating and others, which may be termed values, 85 may be accumulated. Moreover, the arrangement is such, as hereinafter made apparent, that my mechanism or attachment may be employed for shifting the carriage to different columnar positions by operating 90 such attachment independently of the adding machine mechanism.

As hereinbefore suggested during the explanation of the usual operation of the Burroughs machine, the adding wheel pinions 95 which are concerned in the adding or accumulating function of the machine, are alternately removed and restored to operative engagement with the series of racks 610, such pinions being drawn out of mesh 100 or engagement upon the forward stroke of the operating handle and restored to such engagement upon the backward stroke of such handle, with the result that the particular racks actuated communicate to their 105 respective pinions the values represented by their particular keys which were set or operated. My new mechanism or attachment is designed to coöperate or rather interfere with the operation of one of the parts of the 110 machine concerned with this control of the adding wheel pinions and to destroy its usual function whenever desired by the operator. My attachment is also designed to 115 destroy, when actuated by the operator, the operating connection between the rock shaft 100 and the feed arm 513 by breaking the joint or operating connection therebetween, and the same is also designed for and capable of controlling the carriage shift in a 120 manner hereinafter explained.

Referring to my new mechanism or attachment, the same comprises essentially a main operating lever 1 pivoted at a point intermediate its length on a pin or stud 2 125 on some fixed part of the machine and pivotally connected at its forward end to a vertical bar or key stem 3. This key stem passes upwardly through the keyboard of the machine, preferably at the left hand 130

side of the last row of keys on the left, and is provided at its upper end with a key button or special key marked 4. It will be understood that this lever and in fact my entire attachment is arranged at the left hand side of the working parts of the adding machine, as illustrated in Fig. 1; which shows such left hand side of the machine. This lever 1 is a flat bar or strip, which is arranged to move vertically in the same plane as the wipe plate 821 hereinbefore referred to as coöperating with the studs 961 and 961^a for the purpose of alternately removing and restoring the adding wheel pinions as to their engagement with the racks 610. This lever is held with a yielding pressure in its elevated position by means of a spring 5 connected to such lever at a point to the rear of its pivot 2, with the result that such lever is normally held in an inoperative position so as not to affect or interfere with the usual operation of the machine. However, the arrangement is such that upon the depression of the special key 4 the lower edge of this lever will be brought into the path of movement of the wipe plate 821, or rather, as shown, in the path of a pin 821^a secured to the inner side of such wipe plate, as clearly illustrated in Fig. 5, with the result that upon the extreme rearward movement of the arm 813^a such pin 821^a will be contacted by such lower edge of the lever 1 and the wipe plate 821 will thereby be rocked to a substantially horizontal position, at least to such a position as to interfere with its usual coöperation with the stud 961, all as illustrated clearly in Fig. 3. At the completion of the stroke of the operating handle the arm 813^a will be restored to its normal condition, but without operating the three-armed lever 913 or restoring the adding wheel pinions to engagement with the racks. Consequently the item or number which may have been printed by the machine while the special key 4 was in its depressed condition has not been transferred to or accumulated upon the adding wheels. In practice I prefer to provide on the lower edge of the lever 1 a special bearing surface in the form of the depending extension 1^a, although the lower edge of the lever itself could be made to perform the desired result. When the operator releases the special key 4, my attachment will be restored to its normal condition of non interference with the usual workings of the machine.

Referring next to the vertical paper-feed mechanism, the feed arm 1513, in an ordinary Burroughs machine, is moved or rocked rearwardly at every complete stroke of the operating handle, through the medium of the arm 117 secured to the rock shaft 100, and the arm 1513¹, which is actuated by said arm 117 and is itself opera-

tively connected with the feed arm 1513 through the medium of the stud 1539. Still referring to the operation of an ordinary Burroughs machine, when the operating handle is drawn forward, the arm 117 is 70 rocked rearwardly, carrying the lower end of the arm 1513¹ in the same direction, whereupon feed arm 1513 is also rocked rearwardly, through the medium of the stud 1539 working in a substantially vertical slot in such feed arm, and said parts will thereupon be restored to normal position on the backward or return stroke of the main operating handle.

Inasmuch as it is desired to print the 80 items or numbers on the same horizontal line, it is necessary to throw the vertical paper feed mechanism out of action when my new mechanism or attachment is operated, and to this end I provide for destroying the operating connection between the feed arm 1513 and the rock shaft 100. In the present instance I attain such result by providing a joint or connection between the arm 1513¹ and the feed arm 1513. Such latter arm, as particularly shown in Figs. 6, 7 and 8, has a hub which is hung or pivoted upon a stud 1501 secured to the left hand side frame 1066 of the machine. This hub has a shoulder or tooth 6 normally 95 engaged by a pivoted hook 7 which is normally spring-pressed into engagement with such tooth by means of a spring 8, Figs. 7 and 8. This hub is pivoted to the rearward end of a bell crank shaped lever 9, which is hung or pivoted at its middle portion upon the stud 1501. The stud 1539, which in the ordinary Burroughs machine is carried by the arm 1513¹, is secured under the present construction to the lower or forwardly directed arm of the bell crank 9 but engages the slot 1513^a of the lever or rocking arm 1513 in the usual and well known way.

Under the construction just described and with the hook 7 in engagement with its tooth 6, the feed arm will be operated at every stroke of the operating handle as in the ordinary Burroughs machine, but as will be apparent, whenever the engagement between the hook and the tooth is broken or destroyed, the paper feed mechanism will be thrown out of action, inasmuch as the operating connection or joint between the arm 1513¹ and the feed arm 1513 will be broken. In the present instance I provide for the breaking of this joint or operating connection by means of my attachment or lever 1, whose rearward end is downwardly curved and brought adjacent to and parallel with the hook 7 and provided on its upper edge with an inclined bearing or contact surface 1^b, which is arranged to contact a pin or stud 7^a on the outer or left hand side of such hook. Normally this bearing surface lies adjacent such pin 7^a, but does 110 115 120 125 130

not interfere with or affect the usual or normal operation and function of such hook. However, when the special key 4 is depressed and the rearward end of the lever 1 thereby rocked upwardly, the pin 7^a will be contacted by the bearing surface 1^b and forced upwardly and rearwardly, with the result that the connection between the hook 7 and tooth 6 will be destroyed, whereupon the movement of the rock shaft 100 will not be communicated to the feed arm 1513 and the paper feed mechanism will therefore not be operated, Fig. 3. In Figs. 1 and 8 I have illustrated the normal relative condition of these parts and also their normal position when the machine is at a state of rest, but in Fig. 7 I have illustrated the normal relative condition of the parts but showing their relative positions upon the completion of the forward stroke of the main operating handle. In these particular figures of the drawing it will be understood that my attachment is in normal position, that is to say, is inoperative, but in Fig. 6 I have illustrated such normal condition and position in full lines and in dotted lines have indicated the position of the rearward end of the lever 1 when operated and also the "thrown out" or disengaged position of the hook or catch 7. It will be understood that when such hook is disengaged the arm 1513^b moves freely or loosely upon the stud 1501 and its tooth or hook 6 also moves freely, inasmuch as it is not engaged, Fig. 3. Upon the release of the special key the lever 1 will be restored to its normal position by the spring 5 and the hook or catch 7 will be restored to its normal position in engagement with the tooth 6 by means of spring 8.

It will be apparent that my mechanism or attachment as thus far described can be applied to an ordinary Burroughs machine, which will thereby be enabled to print on the same horizontal line one or more items or amounts, some of which may be accumulated as determined by the operator, in which operations the paper carriage may be shifted or adjusted by him to different columnar positions. However, it is desirable to provide for horizontal paper feed by the adjustment or shifting of the paper carriage to such different columnar positions in an automatic manner through the medium of my attachment or new mechanism, which is preferably given this third function as herein provided, in addition to the function of control of the accumulating feature of the machine and the second function of control of the vertical paper feed mechanism.

As hereinbefore stated, the paper carriage is of the laterally shiftable or adjustable type, resembling in general characteristics the carriage of the Pike patent aforesaid, but differing therefrom particularly in the provision of spring tension mechanism tend-

ing to draw the carriage to the left and in the provision of automatically controlled tabulating mechanism whereby the carriage may be released from one columnar position and advanced to another columnar position, 70 said tabulating mechanism being under the control of my attachment hereinbefore referred to.

In the present instance the paper carriage 1568 is mounted to slide laterally in suitable 75 manner at the upper end of a bracket frame 1566 projecting rearwardly from and secured to the rear end of the adding machine case 1167. This bracket frame carries spring tension mechanism comprising the 80 usual spring drum 10 having the usual band 11 fastened in suitable manner to the depending portion 1568^a of the carriage frame, such spring tension mechanism tending to draw the carriage toward the left as 85 viewed from the operator's position, or toward the right as viewed in Fig. 2, but normally restrained by the tabulating mechanism now about to be described.

The tabulating mechanism comprises, in 90 the present instance, a tabulating bar 12 secured to the upper end of the bracket frame 1566 and provided with a series of notches 12^a, with which cooperates a locking dog 13. This locking dog is pivoted in a slot 14 95 formed in a portion 1568^b intermediate of the width of the carriage frame. The locking dog is secured to a rock shaft 15 which extends transversely of the machine and longitudinally of the paper carriage, the same 100 being mounted in bearing lugs 16 near the ends of the carriage frame. The right hand end of this rock shaft is extended beyond its bearings and there provided with a knob or hand wheel 17, whereby the same may be 105 manually operated or manipulated by the operator. A suitable spring 18 connected at one end to the rock shaft serves to normally rock or hold the latter with a yielding pressure in such manner that the locking dog 13 110 will be caused to normally bear against the lower edge of the tabulating bar 12 and to snap into any one of the notches 12^a presented to it. This rock shaft may be operated by merely turning the knob 17, but in the usual 115 operation of my machine it is designed that this rock shaft shall be operated automatically by my new mechanism or attachment hereinbefore described, and to this end I provide a uniyersal bar or bail 19 adapted to be operated by the extended rearward end of my lever 1 and to be operatively connected with the rock shaft 15. In the present instance this operating connection consists of a pair of crank arms 20, from whose outer 120 ends depend links 21 pivotally connected at their upper ends to such crank arms and at their lower ends to levers 22 pivoted intermediate their length to a rod 23 which extends longitudinally of the carriage frame 125 130

and has its bearings in lugs 24 thereof. The forward ends of these levers 22 are connected by said universal rod or bail 19 which extends into close proximity to the rearwardly 5 extending end of the operating lever 1, in whatever position the paper carriage may be, as clearly indicated in Fig. 3.

In order to so time the automatic rocking of the shaft 15 that it will not be operated 10 until after the printing mechanism of the machine has acted and the number or amount has been printed, I provide such rearward end of the lever 1 with a wipe plate 25, which is pivoted to such end of the lever and 15 provided with a finger 25^a extending rearwardly and adapted to intersect the plane of movement of the universal rod when the operating lever 1 is actuated. A spring 25^b serves to hold the wipe plate in its normal 20 position as determined by the contact of another finger 25^c against a pin 25^d arranged on one side of the lever 1.

It will be understood from the foregoing description that when the special key 4 is depressed and the lever 1 thereby caused to interfere with one of the functions of the wipe plate 821 and to break the joint or operating connection of the feed arm 1513 as hereinbefore described, the extreme rearward end of 30 such lever will be rocked upwardly, with the result that the finger 25^a of the wipe plate will slip or flip by the universal rod 19 without affecting the latter; but that upon the return or restoration of the parts to normal position such finger 25^a will press upon the top of such universal rod and force the latter downward, thereby rocking the levers 22, crank arms 20 and rock shaft 15 and releasing the dog 13 from its engagement with the 40 tabulating bar. The spring tension mechanism, being no longer restrained by the locking dog, will draw or advance the carriage to the left until such dog, which has been released just as soon as the finger 25^a cleared 45 the universal rod in its downward movement, engages the next notch to the left of the one previously engaged, with the result that the carriage will now be positioned and locked in the next columnar position to the 50 left.

My invention as hereinbefore described is capable of recording a great variety of accountings and commercial transactions where some of the items are to be accumulated 55 and others not accumulated or added, and for the purpose of affording a clear and comprehensive understanding of the operation and capabilities of such machine I will now proceed to describe the operation thereof in connection with cotton transactions, although it will be understood that this represents only one of the many useful applications of the machine.

In cotton transactions it is required that 60 the number of the bale shall first be printed

and the weight of such bale thereupon printed on the same horizontal line, the number of the bale being, of course, simply printed and not required to be added or accumulated upon the machine but the weights of the 70 bales being added or accumulated on the machine so that a total or footing of such weights may be taken at any time as desired by the operator. Referring now to this particular transaction as an example of the 75 working of my machine, the number of the bale is first set up on the keyboard in the usual manner and the special key 4 is thereupon depressed by the operator, with the result that the lever 1 is brought into the path 80 of the wipe plate 821 when rocked. At the first movement of the operating handle, the pinion frame is swung forwardly out of mesh with the racks by the action of the wipe plate 821 upon the stud 961^a, and upon further movement of such handle the racks descend distances corresponding to the values of the particular keys set.

At the completion of the forward stroke of the operating handle the number represented by the keys set on the keyboard is 90 printed on the paper on the platen, and upon the return stroke of the operating handle the wipe plate 821, being now contacted by the lever 1, is held out of coöperative relation with the stud 961 which it is adapted to contact, under ordinary conditions, for the purpose of restoring the pinion frame 95 before the racks were restored to normal position. Consequently the pinion frame will 100 remain out of mesh or engagement with the racks upon their upward or return movement and the number set up on the key board and printed as described will not be transferred to the adding wheels, that is to say, the number will not be accumulated. The described depression of the special key 4 has also had the effect of breaking the 105 joint or operating connection between the rock shaft 100 and the feed arm 1513, with the result that during the described operation of the machine the platen will not be rotated or turned by the paper feed mechanism and the paper will consequently not be fed vertically as under ordinary conditions. Furthermore, upon the depression of the special key 4 the rearward end of the lever 1 will be rocked upwardly with its 110 wipe plate positioned above the universal rod or bail of the carriage shifting mechanism, so that upon the release of the key and the restoration of its associated parts to normal position, and after the number has been printed upon the platen and the operating handle has been restored to substantially 115 normal position, such wipe plate will rock the bail and thereby release the locking dog from the tabulating bar, with the result 120 that the carriage will be advanced to the next columnar position. In the example 125 130

now being explained, the next item, which will consequently be printed on the same horizontal line as the number of the bale of cotton, is the weight of such bale, which 5 weight is to be accumulated on the machine. This weight is set up on the keyboard and the machine is operated in the usual and well known way, that is to say, the machine is operated as an ordinary Burroughs 10 machine without operating the special key 4. It will be understood that in the printing and accumulating of this item or weight the paper feed mechanism is operated in the usual manner and the platen is turned one 15 line space, ready for the recording of the next transaction. The carriage is shifted by the operator back to the proper columnar position and the number of the next bale of cotton is printed by the machine, which is 20 operated with the special key depressed as hereinbefore described. The carriage is then automatically shifted or advanced one space to the left and the weight of the second bale of cotton is therewith set up on 25 the machine and printed and also accumulated in the usual way. These operations are continued until all the transactions are recorded, a footing or total of the weights 30 of the bales of cotton being taken at any time by the operator.

It will be evident from the foregoing description of the operation of the tabulating mechanism that my special key and connections may be utilized for the purpose of 35 advancing the carriage to different columnar positions without operating the machine, that is, by simply depressing such special key without operating the machine in the usual and well known way, the locking dog 40 will be released and the carriage will be advanced as hereinbefore described. However, when the machine is operated at a time when the special key 4 is depressed, my attachment will exercise its three different 45 functions, first the function of throwing the adding mechanism out of action by interfering with the action of the wipe plate 821, second the function of preventing the 50 operation of the vertical paper feed mechanism, and third the function of controlling the tabulating mechanism or carriage shift, that is the horizontal paper feed.

As hereinbefore suggested, some measure 55 of my invention may be obtained by omitting the rearward extension of the lever 1 which serves to operate the carriage shifting mechanism, leaving such lever or attachment to perform its remaining two functions. With such an attachment the machine is 60 enabled to print numbers or items without accumulating them, but as will be evident the paper feed mechanism will be rendered inoperative during such operations of the machine, but the platen may be line-spaced 65 by hand or, if the numbers or items are to

be printed on the same horizontal line, the carriage may be shifted or advanced by hand to different columnar positions.

It is evident that the proper paper feed may be had and the numbers or items 70 printed without accumulating them by depressing the special key 4 only after the operating handle has been drawn forward to its full extent and the number has been printed on the platen, but before such operating handle and the wipe plate 821 have started back on their return stroke. It will be understood that in such special manipulation of the machine the paper feed mechanism has been moved on the forward stroke 75 of the operating handle whereby the platen is turned thereby upon the return stroke of such handle, and that upon the depression of the special key the wipe plate 821 has been moved or swung to inoperative position, causing the pinion frame to remain out of engagement with the racks. It is thus evident that the advantage of the paper feed may be obtained prior to the time it is necessary to call my attachment into action 80 for the purpose of preventing the accumulation of the number on the adding wheels.

While the key 4 has been described as a device for preventing engagement between the accumulating pinions and their actuating racks at a time when they otherwise would come into engagement, it will be apparent that said key can also serve as a means for preventing disengagement of said pinions from their racks at a time when they 90 otherwise would disengage. Thus, with the total key depressed, causing the pinions to remain in mesh with the racks during the forward stroke of the operating handle, depression of said key 4 will cause the pinions 95 to remain engaged with the racks while the operating handle returns to normal position notwithstanding the continued depression of the total key. In this manner a subtotal can be taken without requiring release of the 100 total key in the middle of an operation. It will of course be obvious that when the key 4 is depressed the wipe pawl 821 cannot cooperate with the stud 961 and hence the accumulator frame C will not be rocked, notwithstanding the engagement of the lower branch 914^b or pitman 914 with the lower 105 stud of said frame. It will therefore be seen that the special key 4 can be readily utilized as a subtotal key with the advantage of not 110 requiring the operator to release the total key 265 at a certain point in the operation of the machine, which is of some importance when an adding machine is being worked under such high speed as to make it difficult 115 to properly time the release of the regular total key.

I claim:

1. In an adding machine, the combination 120 with the adding and printing mechanisms 125

130

thereof, a paper carriage to coöperate with the printing mechanism, mechanism associated with such carriage for feeding the paper vertically and a prime mover for actuating said mechanisms; of a single manipulative means operable at will for throwing out of action both the paper feed mechanism and adding mechanism while leaving the printing mechanism free to operate; substantially as described.

2. In an adding machine, the combination of the adding and printing mechanisms thereof, a paper carriage to coöperate with the printing mechanism, mechanism associated with such carriage for feeding the paper vertically, a prime mover for actuating said mechanisms and means for at will throwing the paper feed mechanism and adding mechanism out of action and a single key controlling said means; substantially as described.

3. In an adding machine, the combination of the adding and printing mechanisms thereof, a laterally movable paper carriage, mechanism associated with said carriage for feeding the paper vertically, a prime mover for actuating said mechanisms, manipulative means operable at will for throwing the adding mechanism out of action and disabling said paper feed mechanism, and means controlled by the same manipulative means for shifting the carriage.

4. In an adding machine, the combination of the adding and printing mechanisms thereof, a laterally movable paper carriage arranged to receive impressions from the printing mechanism, mechanism for shifting or advancing the carriage to different columnar positions, mechanism associated with such carriage for feeding the paper vertically, a prime mover for actuating said mechanisms and single manipulative means for throwing the adding mechanism and paper feed mechanism out of action and for controlling the carriage shift mechanism; substantially as described;

5. In an adding machine, the combination of printing mechanism, adding mechanism comprising actuators and accumulating devices arranged normally to be alternately thrown out of and into coöoperative relationship, a prime mover and connections through which said relationship is controlled, and key set means for disabling said connections at an intermediate stage in the operation of the prime mover, whereby adding is eliminated.

6. In an adding machine, the combination of printing mechanism, adding mechanism having a series of adding wheels and pinions mounted in a swinging frame, an arm 914 controlling the swinging of such frame, a lever 913 connected with arm 914 and normally actuated to swing the arm 914 and the pinion frame to and from operative po-

sition, and means for preventing the movement of the lever 913 to return the frame to operative position; substantially as described.

7. In an adding machine, the combination of printing mechanism, adding mechanism having a series of adding wheels and pinions mounted in a swinging frame, an arm 914 controlling the swinging of such frame, a lever 913 connected with arm 914 and normally actuated to swing the arm 914 and the pinion frame to and from operative position, and means under the control of the operator for preventing the movement of the lever 913 to return the frame to operative position; substantially as described.

8. In an adding machine, the combination of printing mechanism, adding mechanism having a series of adding wheels and pinions mounted in a swinging frame, an arm 914 controlling the swinging of such frame, a lever 913 connected with arm 914 and normally actuated to swing the arm 914 and the pinion frame to and from operative position, and key-controlled means arranged to interfere with the normal operation of the lever 913 to prevent the return of the frame to operative position; substantially as described.

9. In an adding machine, the combination of printing mechanism, adding mechanism having a series of adding wheels and pinions mounted in a swinging frame, an arm 914 controlling the movements of such frame, a lever 913 connected with arm 914, a rocking lever 813 arranged to rock the lever 913 in opposite directions, and means for preventing the return rocking, by said lever 813, of the lever 914 after a rocking in one direction; substantially as described.

10. In an adding machine, the combination of printing mechanism, adding mechanism having a series of adding wheels and pinions mounted in a swinging frame, an arm 914 controlling the movements of such frame, a lever 913 connected with arm 914, a rocking lever 813 arranged to rock the lever 913 in opposite directions, and means under the control of the operator for preventing the rocking of the lever 913 by the lever 813; substantially as described.

11. In an adding machine, the combination of printing mechanism, adding mechanism having a series of adding wheels and pinions mounted in a swinging frame, an arm 914 controlling the movements of such frame, a lever 913 connected with arm 914, a rocking lever 813 arranged to rock the lever 913 in opposite directions, and key-controlled mechanism arranged to interfere with the actuation of the lever 913 by lever 813; substantially as described.

12. In an adding machine, the combination of printing mechanism, adding mechanism having a series of adding wheels and

pinions mounted in a swinging frame, an arm 914 controlling the movements of such frame, a lever 913 connected with arm 914, a rocking lever 813 arranged to rock the lever 913 in opposite directions, a wipe plate carried by the lever 813 for actuating the lever 913 backwardly and forwardly and means for interfering with the operation of the wipe plate and preventing its movement 10 of the lever 913 in one direction; substantially as described.

13. In an adding machine, the combination of printing mechanism, adding mechanism having a series of adding wheels and 15 pinions mounted in a swinging frame, an arm 914 controlling the movements of such frame, a lever 913 connected with arm 914, a rocking lever 813 arranged to rock the lever 913 in opposite directions, a wipe plate carried by the lever 813 for actuating the lever 913 backwardly and forwardly, and a lever under the control of the operator and 20 adapted to interfere with the operation of said wipe plate and prevent the movement 25 of lever 913 in one direction; substantially as described.

14. In an adding machine, the combination of printing mechanism, adding mechanism having a series of adding wheels and 30 pinions mounted in a swinging frame, an arm 914 controlling the movements of such frame, a lever 913 connected with arm 914, a rocking lever 813 arranged to rock the lever 913 in opposite directions, a wipe plate pivoted on lever 813 for actuating the lever 913 in opposite directions; and a lever movable 35 in the path of movement of the wipe plate to render the latter inoperative in one position and thereby prevent the movement 40 of the lever 913 in one direction; substantially as described.

15. In an adding machine, the combination of printing mechanism, adding mechanism having a series of adding wheels and 45 pinions mounted in a swinging frame, an arm 914 controlling the movements of such frame, a lever 913 connected with arm 914, a rocking lever 813 arranged to rock the lever 913 in opposite directions, a wipe plate pivoted on lever 813 for actuating the lever 913 in opposite directions, and a key-controlled lever 1 movable in the path of movement 50 of the wipe plate and adapted to contact the latter and press it to an inoperative position in one position of the lever 813 and thereby prevent the movement of the lever 913 in one direction; substantially as described.

16. In an adding machine, the combination of printing mechanism, adding mechanism having a series of adding wheels and 60 pinions mounted in a swinging frame, an arm 914 controlling the movements of such frame, a lever 913 connected with arm 914, a rocking lever 813 arranged to rock the

lever 913 in opposite directions, a wipe plate pivoted on lever 813 for actuating the lever 913 in opposite directions, and a lever movable into the path of movement of the wipe plate to render the latter inoperative but 70 normally held from such interfering position with a yielding pressure; substantially as described.

17. In an adding machine, the combination of printing mechanism, adding mechanism having a series of adding wheels and 75 pinions mounted in a swinging frame, an arm 914 controlling the movements of such frame, a lever 913 connected with arm 914, a rocking lever 813 arranged to rock the lever 913 in opposite directions, a wipe plate pivoted on lever 813 for actuating the lever 913 in opposite directions, and a lever movable into the path of movement of the wipe plate to render the latter inoperative but 80 normally held from such interfering position with a yielding pressure; substantially as described.

18. In an adding machine, the combination of printing and adding mechanism, a platen for receiving the paper, vertical 90 paper-feed mechanism therefor, a rock shaft, a feed arm co-operating with the paper-feed mechanism and operated by the rock shaft, and means for disconnecting the feed arm and rock shaft; substantially as described. 95

19. In an adding machine, the combination of printing and adding mechanism, a platen for receiving the paper, vertical paper-feed mechanism therefor, a rock shaft, a feed arm co-operating with the paper-feed 100 mechanism and operated by the rock shaft, and means, under the control of the operator, for destroying the operative connection between the feed arm and rock shaft; substantially as described. 105

20. In an adding machine, the combination of printing and adding mechanism, a platen for receiving the paper, vertical paper feed-mechanism therefor, a rock shaft, a feed arm co-operating with the paper-feed 110 mechanism and operated by the rock shaft, and key-controlled means for destroying the operative connection between the feed arm and rock shaft; substantially as described.

21. In an adding machine, the combination of printing and adding mechanism, a platen for receiving the paper, vertical paper-feed mechanism therefor, a rock shaft, a feed arm co-operating with the paper-feed 115 mechanism and operated by the rock shaft, a breakable joint or operative connection between the rock shaft and feed arm, and means for breaking said connection at the will of the operator; substantially as described. 120

22. In an adding machine, the combination of printing and adding mechanism, a platen for receiving the paper, vertical paper-feed mechanism therefor, a rock shaft, a feed arm co-operating with the paper-feed 130

mechanism and operated by the rock shaft, a rock arm 117 on said shaft, an arm or lever 1513½ operated thereby, a feed arm 1513 normally actuated by the movements of said lever 1513½ and having a breakable joint connection with the latter, and means under the control of the operator for breaking the joint at will; substantially as described.

23. In an adding machine, the combination of printing and adding mechanism, a platen for receiving the paper, vertical paper-feed mechanism therefor, a rock shaft, a feed arm coöperating with the paper-feed mechanism and operated by the rock shaft, a rock arm 117 on said shaft, an arm or lever 1513½ operated thereby, a feed arm 1513 normally actuated by the movements of said lever 1513½ and having a breakable joint connection with the latter, a lever 9 operatively connected with said feed arm, a pivoted dog normally holding the lever 9 and lever 1513½ into operative relation, and means for swinging said dog and breaking the connection formed by it; substantially as described.

24. In an adding machine, the combination of printing and adding mechanism, a platen for receiving the paper, vertical paper-feed mechanism therefor, a rock shaft, a feed arm coöperating with the paper feed mechanism and operated by the rock shaft, a rock arm 117 on said shaft, an arm or lever 1513½ operated thereby, a feed arm 1513 normally actuated by the movements of said lever 1513½ and having a breakable joint connection with the latter, a lever 9 operatively connected with said feed arm, a pivoted dog normally holding the lever 9 and lever 1513½ into operative relation, and key-controlled means for swinging said dog and breaking the connection formed by it; substantially as described.

25. In an adding machine, the combination of printing and adding mechanism, a platen for receiving the paper, vertical paper-feed mechanism therefor, a rock shaft, a feed arm coöperating with the paper feed mechanism and operated by the rock shaft, a rock arm 117 on said shaft, an arm or lever 1513½ operated thereby, a feed arm 1513 normally actuated by the movements of said lever 1513½ and having a breakable joint connection with the latter, a lever 9 operatively connected with said feed arm, a pivoted dog normally holding the lever 9 and lever 1513½ into operative relation, said dog being held in said normal position with a yielding pressure, and means for swinging said dog against such pressure and thereby breaking the connection formed by it; substantially as described.

26. In an adding machine, the combination of printing and adding mechanism, a platen for receiving the paper, vertical paper-feed mechanism therefor, a rock shaft,

a feed arm coöperating with the paper-feed mechanism, a rock arm 117 on said shaft, a pivoted arm or lever 1513½ actuated thereby and having a shoulder or tooth 6, a lever or arm 9 operatively connected with the feed arm, a dog 7 carried by such arm 9 and adapted to normally engage said tooth 6 and thereby form the operative connection between the lever 1513½ and the lever 9, and means for swinging the dog and breaking said connection at the will of the operator; substantially as described.

27. In an adding machine, the combination of printing and adding mechanism, a platen for receiving the paper, vertical paper-feed mechanism therefor, a rock shaft, a feed arm coöperating with the paper-feed mechanism, a rock arm 117 on said shaft, a pivoted arm or lever 1513½ actuated thereby and having a shoulder or tooth 6, a stud on which said lever 1513½ is pivoted, a lever or arm 9 also pivoted on such stud and operatively connected with the feed arm, a dog 7 pivoted on said lever 9 and adapted to normally engage said tooth 6 and thereby form the operative connection between the lever 1513½ and the lever 9, and means for swinging the dog and breaking said connection at the will of the operator; substantially as described.

28. In an adding machine, the combination of printing and adding mechanism, a platen for receiving the paper, vertical paper-feed mechanism therefor, a rock shaft, a feed arm coöperating with the paper-feed mechanism, a rock arm 117 on said shaft, a pivoted arm or lever 1513½ actuated thereby and having a shoulder or tooth 6, a stud on which said lever 1513½ is pivoted, a lever or arm 9 also pivoted on such stud and operatively connected with the feed arm, a dog 7 pivoted on said lever 9 and adapted to normally engage said tooth 6 and thereby form the operative connection between the lever 1513½ and the lever 9, and means for swinging the dog and breaking said connection at the will of the operator and comprising a pivoted lever 1 extending adjacent said dog and adapted, when operated, to contact and swing the latter; substantially as described.

29. In an adding machine, the combination of printing and adding mechanism, a platen for receiving the paper, vertical paper-feed mechanism therefor, a rock shaft, a feed arm coöperating with the paper-feed mechanism, a rock arm 117 on said shaft, a pivoted arm or lever 1513½ actuated thereby and having a shoulder or tooth 6, a stud on which said lever 1513½ is pivoted, a lever or arm 9 also pivoted on such stud and operatively connected with the feed arm, a dog 7 pivoted on said lever 9 and adapted to normally engage said tooth 6 and thereby form the operative connection between the lever 1513½ and the lever 9, and means for swing-

ing the dog and breaking said connection at the will of the operator and comprising a pivoted lever 1 extending adjacent said dog which is provided with a pin 7^a against 5 which the lever is adapted, when operated, to bear and thereby swing the dog; substantially as described.

30. In an adding machine, the combination of printing and adding mechanism, a 10 platen for receiving the paper, vertical paper-feed mechanism therefor, a rock shaft, a feed arm coöoperating with the paper-feed mechanism, a rock arm 117 on said shaft, a pivoted arm or lever 1513¹ actuated thereby 15 and having a shoulder or tooth 6, a stud on which said lever 1513¹ is pivoted, a lever or arm 9 also pivoted on such stud and operatively connected with the feed arm, a dog 7 pivoted on said lever 9 and adapted to 20 normally engage said tooth 6 and thereby form the operative connection between the lever 1513¹ and the lever 9, and means for swinging the dog and breaking the connection at the will of the operator and comprising a pivoted lever 1 extending adjacent 25 said dog which is provided with a pin 7^a, said lever having a bearing surface 1^b which bears against the pin; substantially as described.

31. In an adding machine, the combination of the adding and printing mechanisms thereof, a laterally movable paper carriage having carriage shift mechanism for advancing the carriage to different columnar 35 positions, a universal rod or bail connected with said carriage shift mechanism, and a lever for controlling the adding function of the adding mechanism and arranged to actuate the said bail and thereby operate the 40 carriage shift mechanism; substantially as described.

32. In an adding machine, the combination of the adding and printing mechanisms thereof, a laterally movable paper carriage having carriage shift mechanism for advancing the carriage to different columnar positions, a universal rod or bail connected with said carriage shift mechanism, and a lever for controlling the adding function of the adding mechanism and a wipe plate carried on one end of said lever for actuating the bail and thereby operating the carriage shift mechanism; substantially as described.

33. In an adding machine, the combination of the adding and printing mechanisms thereof, a laterally movable paper carriage having carriage shift mechanism for advancing the carriage to different columnar positions, and a lever controlling the adding function of the adding mechanism and adapted to operate the carriage shift mechanism in any position of the carriage; substantially as described.

34. In an adding machine, the combination of the adding and printing mechanisms

thereof, a laterally movable paper carriage having carriage shift mechanism for advancing the carriage to different columnar positions, and a key-controlled lever for controlling the adding function of the adding mechanism and adapted to operate the carriage shift mechanism in any position of the carriage; substantially as described.

35. In an adding machine, the combination of the adding and printing mechanisms 75 thereof, a laterally movable paper carriage having carriage shift mechanism for advancing the carriage to different columnar positions, vertical paper-feed mechanism for the platen, and a lever controlling the 80 adding function of the adding mechanism, the paper-feed mechanism and the carriage shift mechanism; substantially as described.

36. In an adding machine, the combination of the adding and printing mechanisms 85 thereof, a laterally movable paper carriage having carriage shift mechanism for advancing the carriage to different columnar positions, a tabulating bar arranged on the carriage and having a series of notches, a rock shaft provided with a locking dog adapted to engage in any one of the notches presented to it, and a lever for controlling the adding function of the machine and operatively connected with said rock shaft; 90 substantially as described.

37. In an adding machine, the combination of the adding and printing mechanisms thereof, a laterally movable paper carriage having carriage shift mechanism for advancing the carriage to different columnar 100 positions; a tabulating bar arranged on the carriage, a rock shaft provided with a locking dog adapted to coöperate with the bar, a universal rod or bail operatively connected with the rock shaft, and a key-controlled 105 lever for actuating said bail; substantially as described.

38. In an adding machine, the combination of the adding and printing mechanisms thereof, a laterally movable paper carriage having carriage shift mechanism for advancing the carriage to different columnar positions, a tabulating bar arranged on the carriage, a rock shaft provided with a locking dog adapted to coöperate with the bar, a universal rod or bail operatively connected with the rock shaft, and a lever for controlling the adding function of the machine and for actuating said bail; substantially 115 as described.

39. In an adding machine, the combination of the adding and printing mechanisms thereof, a laterally movable paper carriage having carriage shift mechanism for advancing the carriage to different columnar positions, a tabulating bar arranged on the carriage, a rock shaft provided with a locking dog coöoperating with such bar, crank arms on said rock shaft, links depending 125 130

- from such arms, pivoted lever arms connected with the lower ends of such links, a universal rod or bail connected with said lever arms, and a key-controlled lever for actuating said bail; substantially as described.
40. In an adding machine arranged to print upon paper, means for normally feeding the paper vertically, and a prime mover for actuating said means in combination with independent means, under the control of the operator, for feeding the paper horizontally, said means embracing a manipulative device whose manipulation effects the horizontal feed at the same time disabling the first-named means; substantially as described.
41. In an adding machine arranged to print upon paper, means for normally feeding the paper vertically, and a prime mover for actuating said means in combination with independent means, under the control of the operator, for feeding the paper horizontally, said means embracing a key whose depression effects the horizontal feed at the same time disabling the first-named means; substantially as described.
42. In an adding machine arranged to print upon paper, means for normally feeding the paper vertically, and a prime mover for actuating said means in combination with independent means, under the control of the operator, for throwing out the vertical paper feed and itself effecting horizontal feed; substantially as described.
43. In an adding machine having a laterally movable paper carriage, the combination with such carriage and a prime mover of means actuated thereby for normally feeding the paper vertically, and independent means under the control of the operator for feeding the paper horizontally through lateral movement of said carriage, said means including a manipulative device whose manipulation effects such movement at the same time disabling the first-named means; substantially as described.
44. In an adding machine having a laterally movable paper carriage, the combination with such carriage and a prime mover of means actuated thereby for normally feeding the paper vertically, and independent key-actuated means under the control of the operator for feeding the paper horizontally through lateral movement of said carriage, said means including a manipulative device whose manipulation effects such movement at the same time disabling the first-named means; substantially as described.
45. In an adding machine having a laterally movable paper carriage, the combination with such carriage and a prime mover of means actuated thereby for normally feeding the paper vertically, and independent key-actuated means under the control of the operator for feeding the paper horizontally through lateral movement of said carriage, said means including a manipulative device whose manipulation effects such movement at the same time disabling the first-named means; substantially as described.
46. In an adding machine the adding and printing mechanism thereof, in combination with means for feeding the paper vertically, means for feeding the paper horizontally, and a single key-actuated means under the immediate control of the operator for governing the adding mechanism and the two paper feeding means and arranged to render them operative or inoperative at will to column-space only or to line-space and add; substantially as described.
47. In an adding machine, the adding and printing mechanism thereof, in combination with a paper carriage arranged for automatic line spacing and for horizontal spacing but normally arranged to line space only, and means under the operator's control and adapted, when operated, to throw out the line spacing and itself perform the horizontal spacing; substantially as described.
48. In an adding machine, the adding and printing mechanism thereof, in combination with paper carriage mechanism arranged for automatic line spacing and for horizontal spacing but normally arranged to line space only, and a special key and connections under the operator's control for controlling said spacings and arranged to render the line spacing inoperative and to themselves perform the horizontal spacing; substantially as described.
49. In an adding machine, arranged to print upon paper, vertical paper feed mechanism, a handle having connection with the adding mechanism and paper feed mechanism for operating them, and means under the control of the operator for breaking said operating connection and thereby through one and the same act eliminating both the adding and paper feed functions of the machine; substantially as described.
50. In an adding machine arranged to print upon paper, vertical and horizontal paper feed mechanisms, a handle having operating connection with the vertical paper feed mechanism, and means under the control of the operator for breaking said operating connection thereby through one and the same act throwing the vertical paper feed mechanism out of action and throwing the horizontal paper feed mechanism into action; substantially as described.
51. In an adding machine arranged to print upon paper, vertical and horizontal paper feed mechanisms, a handle having operating connection with the vertical paper feed mechanism, and a special key and

connections, by the operation of which key the said operating connection is broken, thereby throwing the vertical paper feed mechanism out of action and simultaneously bringing the horizontal paper feed mechanism into action; substantially as described.

52. In an adding machine arranged to print upon paper, vertical and horizontal paper feed mechanisms, a handle having operating connection with the vertical paper feed mechanism, and a special key and connections arranged, when operated, to break said operating connection, thereby eliminating the vertical paper feed, and to eliminate the adding function of the machine and also to bring the horizontal paper feed mechanism into action; substantially as described.

20 53. An adding machine having adding and printing mechanism, value keys and a total key therefor, an operating handle for the machine, a paper carriage arranged for automatic line spacing and horizontal spacing, and means under the operator's control for controlling the spacings, whereby, in the normal operation of the machine, line spacing is accomplished automatically and, when said means are operated, the line spacing is omitted and horizontal spacing effected; substantially as described.

35 54. In an adding machine, the combination of printing mechanism, adding mechanism having actuators and a series of adding wheels or dials arranged to be thrown into and out of operative relation therewith; a wipe block or plate normally controlling said relationship and means, under the control of the operator, for rendering 40 said wipe plate inoperative to restore the dials to their operative relation with the actuators; substantially as described.

45 55. In an adding machine, the combination of printing mechanism, adding mechanism having actuators and a series of adding wheels or dials arranged to be thrown into and out of operative relation therewith, a prime mover, and connections for so throwing the said dials including a pivoted 50 and swinging wipe plate, and a lever under the control of the operator and arranged to be interposed in the path of movement of the wipe plate and to rock the latter on its pivot, thereby rendering such plate inoperative in one position and preventing its coöperation with the dials at such time; substantially as described.

60 56. In an adding machine, the combination of printing mechanism, adding mechanism having actuators and a series of adding wheels or dials arranged to be thrown into and out of operative relation therewith, a prime mover, and connections for so throwing the said dials including a rock 65 arm, a wipe plate pivoted thereon, operat-

ing connections between the dials and wipe plate, and means, under the control of the operator, for rocking the plate on its pivot in one position of said rock arm and thereby preventing actuating of said operating connections at said time; substantially as described.

70 57. In an adding machine, the combination of printing mechanism, adding mechanism having actuators and a series of adding wheels or dials arranged to be thrown into and out of operative relation therewith, a prime mover, and connections for so throwing the said dials including a rock arm, a wipe plate pivoted thereon, operating connections between the dials and wipe plate, and a pivoted lever arranged to be interposed in the path of movement of the plate and to thereby rock the latter to prevent, at such time, the normal actuation of 80 the operating connections and the dials; substantially as described.

85 58. In an adding machine, the combination of printing mechanism, adding mechanism having a series of adding wheels or dials mounted in a rocking frame, operating connections for controlling the rocking of such frame, a swinging wipe plate for actuating said connections, and means under the operator's control for rendering the wipe 90 plate inoperative in one position of its movement; substantially as described.

95 59. In an adding machine, the combination of printing mechanism, adding mechanism having a series of adding wheels or dials mounted in a rocking frame, operating connections for controlling the rocking of said frame, a swinging wipe plate for actuating said connections, and a key-controlled 100 lever arranged to be interposed in the path of movement of the wipe plate and to render the latter inoperative when contacted thereby; substantially as described.

105 60. In an adding machine, the combination of printing mechanism, adding mechanism having a series of adding wheels or dials mounted in a rocking frame, operating connections for controlling the rocking of said frame, a swinging wipe plate for actuating said connections, and a key-controlled 110 lever normally spring-pressed to an inoperative position but arranged to be interposed in the path of movement of the wipe plate and to render the latter inoperative when contacted thereby; substantially as described.

115 61. In an adding machine, the combination of printing mechanism, adding mechanism having a series of adding wheels or dials mounted in a rocking frame, operating 120 connections for controlling the rocking of said frame, a swinging wipe plate for actuating said connections, a contact stud on said wipe plate, and a key-controlled lever arranged to be interposed in the path of 125

said stud of the plate to rock the latter and thereby prevent its coöperation with the said operating connections under said conditions; substantially as described.

5 62. In an adding machine, the combination of printing mechanism, adding mechanism having a series of adding wheels or dials mounted in a rocking frame, a rock arm having operative connection with the 10 rocking frame, and means for destroying said operative connection at one position of the rock arm and thereby preventing a rocking of the frame in one direction; substantially as described.

15 63. In an adding machine, the combination of printing mechanism, adding mechanism having a series of adding wheels or dials mounted in a rocking frame, a rock arm having operative connection with the 20 rocking frame, and a key-controlled device under the control of the operator for destroying said operative connection at one position of the rock arm and thereby preventing a rocking of the frame in one direction; 25 substantially as described.

30 64. In an adding machine, the combination of printing and adding mechanisms, a paper carrier having a vertical paper feed normally automatically actuated in the operation of the machine, and key-actuated means under the control of the operator for rendering the adding mechanism inoperative after the actuation of the paper feed mechanism; substantially as described.

35 65. In an adding machine, the combination of printing and adding mechanisms, a paper carrier having a vertical paper feed, a prime mover and means controlling said paper feed and the adding mechanism and 40 arranged to render both the paper feed and adding mechanism inoperative or the adding mechanism alone inoperative according to whether setting of said means occurs before or at an intermediate stage in the 45 operation of the prime mover; substantially as described.

50 66. In an adding machine, the combination of printing and adding mechanisms, a paper carrier having a vertical paper feed, a prime mover, and key-actuated means under the control of the operator for controlling said paper feed and the adding mechanism and arranged to render both the paper feed and adding mechanism inoperative or 55 the adding mechanism alone inoperative according to whether setting of said means occurs before or at an intermediate stage in the operation of the prime mover; substantially as described.

60 67. In an adding machine, the combination of printing and adding mechanisms, a prime mover, a paper carrier having a vertical paper feed normally active for line spacing, and means under the control of the operator whereby in a single operation of

the prime mover printing without adding and without line spacing may be accomplished, or printing without adding but after line spacing.

68. In an adding machine, the combination of printing and adding mechanisms, an operating handle for actuating such mechanisms, a paper carrier having a vertical paper feed for line spacing normally actuated by the movements of such handle, and means under the control of the operator for controlling the adding mechanism and the paper feed and adapted to render them inoperative, said means being constructed and arranged to render both the adding mechanism and paper feed inoperative when operated at the beginning of the movement of the operating handle or only the adding mechanism when such means are operated during the movement of such handle; substantially as described.

69. In an adding machine, the combination of printing and adding mechanisms, an operating handle having a forward and backward movement for actuating such mechanisms, a paper carrier having a vertical paper feed for line spacing normally actuated by the movements of such handle, and means under the control of the operator for controlling the adding mechanism and the paper feed and adapted to render them inoperative, said means being constructed and arranged to render both the adding mechanism and paper feed inoperative when operated at the beginning of the movement of the operating handle or only the adding mechanism when such means are operated at the end of the forward movement of the operating handle; substantially as described.

70. In an adding machine, the combination of adding and printing mechanisms, means for line spacing the paper, means for horizontal spacing thereof, and means under the control of the operator for controlling the adding mechanism and the two paper spacings and for rendering them operative or inoperative at will, said means being constructed and arranged when actuated at one time in the period of operation of the machine to render the adding mechanism and line spacing inoperative and the horizontal spacing operative and at another time to render the adding mechanism alone inoperative; substantially as described.

71. In an adding machine, the combination of adding and printing mechanisms, an operating handle having a forward and rearward movement for actuating such mechanisms, means normally controlled by the handle for line spacing the paper, means for horizontally spacing the paper, and key-controlled means under the control of the operator for controlling the adding mechanism and the two paper spacings and for rendering them operative and inoperative at will,

said means being arranged, when operated substantially at the beginning of the forward movement of the handle, to render the adding mechanism and line spacing inoperative and the horizontal spacing operative, and, when operated at the end of such forward movement, to render the adding mechanism alone inoperative after the normal actuation of the line spacing; substantially as described.

72. In an adding machine, the combination of the adding and printing mechanisms thereof, a laterally movable paper carriage having carriage shift mechanism for advancing the carriage to different columnar positions, a tabulating bar arranged on the carriage, a rock shaft provided with a locking dog adapted to coöperate with the bar, a universal rod or bail operatively connected with the rock shaft, and a key-controlled lever carrying a wipe plate at its outer end for actuating said bail; substantially as described.

73. In an adding machine, the combination of the adding and printing mechanisms thereof, a paper carrier, line spacing mechanism coöperating therewith, a prime mover for actuating said mechanisms and single means for throwing the line spacing mechanism and adding mechanism out of action; substantially as described.

74. In an adding machine, the combination of the adding and printing mechanisms thereof, a paper carrier, line spacing mechanism coöperating therewith, a prime mover for actuating said mechanisms and single key-controlled means for throwing the line spacing mechanism and adding mechanism out of action; substantially as described.

75. In an adding machine, the combination of the adding and printing mechanisms thereof, a paper carrier, line spacing mechanism coöperating therewith, a prime mover for actuating said mechanisms and single means normally inoperative but arranged to be rendered operative to interfere with the adding mechanism and line spacing mechanism for rendering them inoperative; substantially as described.

76. In an adding machine, the combination of the adding and printing mechanisms thereof, a laterally movable paper carriage having vertical and transverse feeds with independent actuating mechanisms, and a single manipulative means for controlling both feeds and rendering them alternately operative and inoperative manipulation of said means itself effecting the transverse feed while eliminating the vertical feed; substantially as described.

77. In an adding machine, the combination of the adding and printing mechanisms thereof, a laterally movable paper carriage having vertical and transverse feeds with independent actuating mechanism, and a

single manipulative means under the control of the operator for rendering said feeds alternately operative and inoperative at will manipulation of said means itself effecting the transverse feed while eliminating the vertical feed; substantially as described.

78. In an adding machine, the combination of the adding and printing mechanisms thereof, a laterally movable paper carriage having vertical and transverse feeds with independent actuating mechanisms, a single means for controlling both feeds and rendering them alternately operative and inoperative, and a special key for operating said means, the depression of which key itself effects the transverse feed while eliminating the vertical feed; substantially as described.

79. In an adding machine, the combination of the adding and printing mechanisms thereof, a laterally or transversely movable paper carriage, mechanism controlling the shifting or transverse feed of the carriage, and a single means for throwing out of action both the adding mechanism and the feed controlling mechanism while leaving the printing mechanism free to operate; substantially as described.

80. In an adding machine, the combination of the adding and printing mechanisms thereof, a prime mover for actuating said mechanisms, a laterally or transversely movable paper carriage, mechanism controlling the shifting or transverse feed of the carriage, means for throwing out of action the adding mechanism, means for releasing the feed controlling mechanism, and a special key for operating both said means; substantially as described.

81. In an adding machine, the combination of the adding and printing mechanisms thereof, a laterally movable paper carriage having a roller or platen adapted to co-operate with the printing mechanism, line spacing mechanism coöperating with the platen, and means for throwing out of action both the adding mechanism and the line spacing mechanism at any position of the carriage; substantially as described.

82. In an adding machine, the combination of the adding and printing mechanisms thereof, a laterally movable paper carriage having carriage shift mechanism, a universal rod connected with said carriage shift mechanism, and means arranged to actuate said rod and to render the adding mechanism inoperative; substantially as described.

83. In an adding machine, the combination of the adding and printing mechanisms thereof, a laterally movable paper carriage having carriage shift mechanism, a universal rod connected with said carriage shift mechanism, and key-controlled means arranged to actuate said rod and to render the adding mechanism inoperative at the

will of the operator; substantially as described.

84. In a machine of the character described, the combination with adding mechanism, line spacing mechanism and normally restrained column spacing mechanism, of means for disabling the adding and line spacing mechanism and releasing the column spacing mechanism.

10 85. In a machine of the character described, the combination with adding mechanism and line spacing mechanism and a prime mover for actuating said mechanisms, of a single manipulative means for simultaneously disabling both mechanisms at the will of the operator.

15 86. In a machine of the character described, the combination with adding mechanism and column spacing mechanism, a prime mover for actuating said mechanisms of a single means for disabling the adding mechanism and causing the column spacing mechanism to act.

20 87. In a machine of the class described, the combination with the register actuating racks and register normally in engagement with said racks, of the main shaft, mecha-

nism operated by the main shaft for normally disengaging and reengaging the racks and register while accumulating amounts, 30 and a sub-total key adapted to disconnect said mechanism from the main shaft.

88. The combination with the forked pitman and reciprocating arm and connections, of a controller adjustable to put the pitman 35 into and out of operative connection with the arm.

89. In a machine of the character described, the combination with the forked pitman, oscillating arm and its pawl, and three armed lever 913, of means adjustable to put the arm and pitman into and out of operative connection.

90. In a machine of the character described, the combination with the forked pitman, of devices for reciprocating the same, and a controller adjustable to render said devices operative or inoperative on the pitman.

ALVAN MACAULEY.
